UNITED STATES PATENT OFFICE

MALKAN A. PEARLMAN, OF CHICAGO, ILLINOIS

DESIGN FOR A DECK OF PLAYING CARDS OR THE LIKE

Application filed October 26, 1932. Serial No. 45,592. Term of patent 3½ years.

To all whom it may concern:

Be it known that I, MALKAN A. PEARLMAN, a citizen of the United States of America, residing at Chicago, in the county of Cook, and State of Illinois, have invented a new, original, and ornamental Design for a Deck of Playing Cards or the like, of which the following is a specification, reference being had to the accompanying drawings, forming a part thereof.

The drawings show the ace, king, queen, and jack of each of the four suits for a deck of playing cards, all of which can be readily identified with all the other cards of the deck without the use of other designations.

I claim:

The ornamental design for a deck of playing cards or the like, substantially as shown and described.

MALKAN A. PEARLMAN.
